(57) **CLAIM**

We claim the ornamental design for a shower, as shown and described.

DESCRIPTION

FIG. 1 is a front view of the shower; and,

FIG. 2 is a perspective view of the shower of FIG. 1.

Any broken line showing of the environment is for illustrative purposes only and forms no part of the claimed design. The broken lines having unequal length segments illustrate the boundaries of the claimed design and form no part of the claimed design.
